HIS ATTORNEYS.

UNITED STATES PATENT OFFICE

JAMES LYLE MILLER, OF TOLEDO, OHIO, ASSIGNOR TO REX RESEARCH CORPORATION, OF TOLEDO, OHIO, A CORPORATION OF DELAWARE

CLEANER SET PACKAGE

Application filed May 22, 1928. Serial No. 279,673.

This invention relates to packing means for putting up various kinds of separate liquids together, and especially to packaging for distributing a "line" of cleansing liquids in the 5 form of a set.

There is no single cleansing agent on the market capable by itself of cleaning and removing satisfactorily and safely all the numerous different kinds of spots encountered in 10 daily life, particularly in the household. For instance, there are cleansing agents for removing ink spots, others for removing grease and gum, and still others for removing rust and grass stains, etc., but no one of these 15 agents will do by itself for all of these different kinds of spots.

It is the chief object of the present invention to make up a package of an improved type out of a number of different kinds of 20 cleansing agents, each in a separate container in such a manner as to provide a single, unitary article in the form of a permanent package-set adapted particularly well for display, but still better adapted for use as a household 25 convenience capable of taking care of all spot-removing and other cleaning needs.

It is a particular object of the invention to provide a package which will have means for holding these separate containers in small 30 compass, yet in such a way that they cannot collide with each other during shipping and break or spill, or become disarranged, and whereby ready access, easy removal, and simplicity of handling will not be hindered, but 35 will instead be enhanced.

It is a further particular object of the invention to improve the structure of certain 40 of the elements of which packages are made, primarily to cheapen the cost of production of the package, but also to so simplify and strengthen the structure as a framework, as to adapt it to successfully withstand the hard battering incident to shipping and service, 45 and at the same time to confer upon it nevertheless a pleasing, attractive appearance.

A typical form of the invention will be described in conjunction with the accompanying drawings, but the inventive idea is limited in

its embodiments only by the scope of the subjoined claims.

In these drawings—

Fig. 1 is a perspective of one of the package-forming elements before being assembled 55 into the package;

Fig. 2 is a perspective of another one of the package forming elements by itself;

Fig. 3 is a perspective of the completed package ready for display or use; 60

Fig. 4 is a section on line 4—4 of Fig. 3 showing the structure of one of the packing elements;

Fig. 5 is a section on line 5—5 of Fig. 4, and

Fig. 6 is a section partly in plan, of the article, on line 6—6 of Fig. 4, showing the bottom and side structure of the completed package. 65

In the form of the invention shown in the drawings, all the parts used in making up the 70 package are contemplated as being made of some suitable sheet-material flexible enough to permit of the parts being easily bent into shape, and then have their ends united by simple fastening means, such as eyelet-brads, 12, 75 or the like.

One of these package parts consists of a strip of sheet-material 8, most clearly shown in Fig. 2, of such a flexible nature that it can be readily bent by hand, but yet of a certain 80 rigidity nevertheless. This member is bent in plan as shown in Fig. 6, and has its ends united by a rivet, or eyelet, or other means 10, passing through the punch-holes 10' and 10", thus forming a substantially rectangular 85 frame 8 on and around which the rest of the package is built. The strip 8 in addition has its lower edges, all around, bent or shaped into a substantially horizontal extension to thereby form flanges 20. 90

Another one of the package elements consists of a more extensive sheet of more flexible material 5. This member is supported on and within the frame 8 by its upper ends only, which are turned up for suspension 95 from the upper edges of two opposite sides of the frame 8, as shown in Figs. 4 and 5. This member thus acts as a sort of spring-cushion due to its flexibility and manner of attachment, and absorbs all the shocks and 100

strains which would otherwise come on the containers 6 to their detriment. The member 5 is prevented from sagging down out of the open bottom of the package, under the weight of the containers, when it contacts near its middle with the flanges 20; if preferred, however it may be attached to these flanges, at any desired place and by any suitable fastening means, such as the eyelets 23.

10 The third member of the package is a lid preferably made of a sheet of semi-flexible material 7, which lid clamps down over and around all the upper edges of the frame or base-member 8 except the back edge. The 15 rack or suspension member 5 thereby has the receptacles or the like pressed down and sideways against it and the containers are thus held in a small compass yet safe from harm. The member 7 has three of its edges turned down, as shown, to engage over the edges of the member 8, and is attached so as to clear along its fourth edge to both the frame and the rack. This attachment, whereby the 20 spring effect of the rack 5 is preserved, is made by suspending the member 5 from the top edge of two sides of the frame 8 by the same means as by which the lid is attached to the frame.

25 In the preferred form of this suspension, an extra long eyelet or brad or the like, 12, is passed through the upper ends of the member 5, through the frame 8, and then anchored over the rear ends of the two side edges of the member 7. There is thus evolved a 30 combined pivot, attaching, and bracing structure, as shown best in Fig. 4, without the use of any loose or expensive parts which preserves the spring-effect of the rack, yet is 35 sturdy enough to serve well under the abuses 40 a package of this kind receives.

The sheet 5 is provided with a number of troughs or transverse grooves 30, which are pressed in the flexible material, and can thus vary in size and shape or be distorted under 45 the pressure of the various shapes of articles made up into a package-set according to the present invention. These articles usually 50 comprise a plurality of cylindrical containers, 6, under the middle one of which is placed a zinc-plate 6' and a folded piece of 55 chamois 6''. This element 5 is quite flexible, the containers 6 and other articles which are to be packed, do not necessarily have to be of a cylindrical shape, since when the third 60 member of the package is forced down on these containers, the strip 5 will be slightly but sufficiently, distorted by the pressure of the containers in such a manner that the containers will be satisfactorily held yieldingly 65 together to prevent collision, yet in predetermined spaced relation sufficiently wide for easy access. This member 5 thus constitutes at one and the same time, a rack holder, and a suspension cushion protective member, 70 thereby obviating special outside protective

packing for shipping, yet without increasing the cost.

By the present invention, there is thus provided an improved household article ready 70 for instant use to meet all needs for any kind of a spot-remover, yet having such a structure that it permanently retains its original form, 75 notwithstanding well the abuses and accidents arising in the home or in shipping, yet constituted by these same means, an article of 80 quite a pleasing and attractive appearance.

I claim:

1. A package of liquid cleaning-materials in receptacles including a container comprising a frame having an open bottom, a flexible 80 member suspended from the top edges of two sides thereof for carrying the receptacles and having formations thereon for protecting the receptacles from contacting with each other and with outside objects, said frame having 85 its lower edges all around formed into substantially horizontal flanges and extended under said flexible member a sufficient distance to prevent said member from sagging down and out of the package under the weight 90 of the receptacles.

2. A cleaning material package, comprising 95 a main package-forming portion of flexible sheet-material having formations for resiliently holding a plurality of liquid containers in frictional relation to itself and to each other therein, portions of said sheet-material extending up between said containers, another portion formed vertically 100 around and horizontally under the edges of said main portion and comprising a strip of substantially rigid material having its ends united, and a piece of semi-flexible sheet material hingedly attached to said main portion and swingable downwardly for clamping 105 said containers in said main portion.

3. A package of liquid cleaning materials, comprising a package-outlining base portion, 110 said portion having formations therein for holding together a plurality of liquid containers, said formations preventing said containers from contacting each other and from changing location in the package, a member swingably attached to two corners of said base portion and supported when in its 115 lowered position by said containers, and another package-portion comprising a single strip of sheet-material formed vertically around said base portion, and having its lower edges turned horizontally and having 120 its sides united to the base portion by the same means which attach said swingable member to the base portion.

4. In a package of the class described, a 125 bottom-portion having a corrugated surface for holding a plurality of cylindrical containers in spaced relation therein, and having each end turned up, a four-square guard portion attached around said ends, and a member for clamping said containers in said 130

bottom, comprising a portion of sheet-material hingedly attached to the bottom over and through the upper part of said guard strip to thereby hold said strip and said member to said bottom.

5 In testimony whereof I affix my signature.
JAMES LYLE MILLER.
